UNITED STATES PATENT OFFICE.

ALBERT O. HILLEY, OF WACO, TEXAS.

BURGLAR-ALARM.

1,217,175.

Specification of Letters Patent. Patented Feb. 27, 1917.

Application filed October 15, 1915. Serial No. 56,039.

To all whom it may concern:

Be it known that I, ALBERT O. HILLEY, a citizen of the United States, residing at Waco, in the county of McLennan and State 5 of Texas, have invented certain new and useful Improvements in Burglar-Alarms; and I do hereby declare the following to be a full, clear, and exact description of the invention, such as will enable others skilled 10 in the art to which it appertains to make and use the same.

This invention relates to new and useful improvements in burglar alarms and the principal object of the device is to provide 15 a burglar alarm consisting of a means for automatically closing a circuit upon the entrance of unauthorized persons into a building either through the door or window.

Another object of the device is to provide 20 a means for operating the signals in such a way that the person entering the building will be unaware of the fact that he has given the alarm.

A further object of the invention is to 25 provide a device which may be readily attached to an ordinary electric circuit without the necessity of placing wires or otherwise rearranging the circuit.

With these and other objects in view, the 30 invention consists in the novel combination and arrangement of parts which will be fully set forth in the following specification and accompanying drawings, in which:

Figure 1 is a view of a portion of a window illustrating my improved burglar alarm attached thereto.

Fig. 2 is an enlarged side elevation of the burglar alarm.

Fig. 3 is an end view of the device.

40 Referring now to the drawings by characters of reference, the numeral 1 designates a window of the usual construction provided with the usual sash 2, which is slideable in the window casing designated by the 45 numeral 3. Secured to one side of the casing is a hook 4 and to the opposite side an eye 5 and the hook forms an attaching means for the cord which passes through the eye as clearly shown in the drawings.

50 The burglar alarm is designated by the numeral 6 and comprises the base board or plate 7 which may be of any suitable material and finished in any desired manner. Secured to this board 7 are the signal sockets 55 8 in which various signaling appliances are

retained. In the uppermost socket 8 is shown a lamp 9 of the incandescent type and the lighting of this lamp and the operation of the various signals is controlled by the switch 10, the pole 11 of which is connected to the feed socket 12 which is mounted at one end of the board 7. The opposite pole 13 of the switch is connected by suitable wires which are preferably embedded in the base 7 to the various distributing 60 sockets 8 so that when the switch is closed, the current will flow through the various signals. The upper end of the base board carries an eye 14 and the lower end is provided with a suitable hook or other attaching means 15 by which the device may be secured to the wall. A suitable attachment plug 16 is threaded into the feed socket 12 and is provided with the feed wires 13^a having connected at their opposite ends, 70 the plug 17. A suitable switch preferably of the pendant type 18 is connected in one of the wires and is provided with the wire 19 leading therefrom so that the switch may be positioned at a point distant from the 75 alarm.

Threaded into the distributing sockets 8 are suitable connecting plugs 20 having connected thereto the wires 21 which lead therefrom to suitable lamp sockets 22 or any other 85 suitable means and mounted in the lamp socket are the signal lamps 23. The wires 21 may be of varying lengths in order that the signal lamps and signals may be positioned in various parts of the building so 90 as to give the signal in a distant place.

In order to operate the signal there is provided the flexible member designated by the numeral 24, one end of which passes through the eyes 25 secured to the base 7 and is connected to the switch lever 26. The opposite end of the flexible member has attached thereto the securing members 27 comprising a pair of converging arms 28 formed with the spring loop 29 and these arms are forced 100 between the eye 4 on the window frame as illustrated in Fig. 1. It will thus be seen that the flexible member will be held tightly across the window between the eyes 4 and 5 and any person entering the window will 105 exert pull on the same thereby moving the switch arm 26 into engagement with the contact 13.

It is to be understood that if so desired a suitable transformer 30 may be connected 110

to one of the attachment plugs 20 and will serve to operate the bell 31 or similar signals when the circuit is closed therethrough.

It will be evident from the foregoing that the device may be provided with any number of flexible members 24 and when pull is exerted on any one thereof, it will be evident that the switch arm will be moved into contact with the pole 13 thus closing the circuit to the various signaling devices and in event that the transformer and bell is connected to one of the sockets it will be evident that the signal connected to the secondary of the transformer will be operated. It is to be understood that if so desired suitable plug sockets may be connected to the brackets 8 in such a manner that a number of flexible cords 21 may be connected to a single socket, thereby increasing the number of places in which the signal may be given.

While in the foregoing there has been shown and described the preferred embodiment of this invention, it is to be understood that such changes may be made in the combination and arrangement of parts as will fall within the spirit and scope of the appended claims.

What is claimed is:—

1. A signal of the character described comprising a base, a plurality of distributing sockets on said base, a feed socket on the base, wires connecting one of the distributing sockets with the feed socket, means to close a circuit through the distributing sockets upon the entrance of an unauthor-

ized person into the building, and signals connected to the other distributing sockets and operated upon the closing of the circuit.

2. A burglar alarm comprising a base, a plurality of distributing sockets on the base, signals connected with the distributing sockets, a feed socket on the base, a source of electric current connected to the feed socket, a switch between the feed socket and one of the distributing sockets and means connected to the switch to close the same upon the entrance of a person into the building to operate the signals.

3. A burglar alarm comprising a base, a plurality of distributing sockets mounted on the base, a feed socket on the base, a power source connected to the feed socket, wires connecting the feed socket with the distributing sockets, a switch controlling the flow of current through the distributing sockets, signals connected to the distributing sockets, a flexible member connected to the switch and passing in front of the doors and windows of a building in which the device is used and means to hold the flexible member in place whereby upon the entrance of an unauthorized person into the building the switch will be closed and the signals operated.

In testimony whereof I affix my signature in presence of two witnesses.

ALBERT O. HILLEY.
